Patented Nov. 13, 1973

229,228

CABINET FOR KEYBOARD INSTRUMENT

Edward Barczak, Los Angeles, and Adolph D. Lambach,
Fountain Valley, Calif., assignors to Opsonar Organ
Corporation, Bronx, N.Y.

Original design application Jan. 11, 1971, Ser. No.
105,793, now Patent No. 224,270. Divided and
this application Mar. 6, 1972, Ser. No. 232,345

Int. Cl. D17—01

U.S. Cl. D56—2

FIG. 1

FIG. 3

FIG. 5

FIG. 6

FIG. 2

FIG. 4

FIG. 7

FIG. 1 is a perspective view of a cabinet for keyboard instrument embodying our design;

FIG. 2 is a front elevational view thereof;

FIG. 3 is a right side view thereof;

FIG. 4 is a left side view thereof;

FIG. 5 is a top plan view thereof;

FIG. 6 is a bottom view thereof; and

FIG. 7 is a rear elevational view thereof.

This is a division of patent application Ser. No. 105,793 filed Jan. 11, 1971 by Salvatore Merendino; Edward Barczak and Adolph D. Lambach, now Pat. No. D-224,270 of July 11, 1972.

We claim:

The ornamental design for a cabinet for keyboard instrument, as shown and described.
